(No Model.)

S. C. WOOD.

AUTOMATIC BARREL REGISTER.

No. 548,243.

Patented Oct. 22, 1895.

UNITED STATES PATENT OFFICE.

SOLOMON C. WOOD, OF WEST ORANGE, NEW JERSEY, ASSIGNOR TO HIMSELF,
AND HENRY J. BANG, OF NEW YORK, N. Y.

AUTOMATIC BARREL-REGISTER.

SPECIFICATION forming part of Letters Patent No. 548,243, dated October 22, 1895.

Application filed February 25, 1895. Serial No. 539,619. (No model.)

To all whom it may concern:

Be it known that I, SOLOMON C. WOOD, a citizen of the United States, residing at West Orange, in the county of Essex and State of New Jersey, have invented an Improvement in Automatic Barrel-Registers, of which the following is a specification.

Registers have heretofore been made in which a lever is moved by the barrel or package passing along a skid or conveying device adjacent to such lever, the lever being moved to a greater or less extent, according to the size of the passing barrel or other article, and in some instances a register or counting device has been moved mechanically and in other instances electrically, as will be seen upon reference to Letters Patent No. 526,140, granted September 18, 1894, to H. J. Bang.

In the present instance a compound lever is made use of, the two parts being moved together, or nearly so, until such compound lever has been fully moved, according to the size of the article passing beneath the same, and thereafter a portion of the compound lever receives a secondary movement by the passing article, and the connections to the counting or registering devices are so made and arranged that the primary movement of the lever determines which of the counting or registering devices is to be actuated, such register being the one allotted to the particular size of barrel or other article that is passing the registering apparatus, and the movement given to the secondary lever or connected apparatus actuates the said registering or counting mechanism, thus insuring accuracy in the registering or counting devices with any size of barrel or other article that may pass adjacent to the compound lever.

In the drawings, Figure 1 is a side view of the improvement as applied in connection with an elevating device. Fig. 2 is an elevation, partially in section, of the compound lever and the arms therewith connected at right angles to Fig. 1. Fig. 3 is an elevation of a modification representing mechanical connections to the registering devices. Fig. 4 shows an elevation of a modification of the electric connections, and Fig. 5 a plan view of the same.

The barrel A or other article is to be moved

past the registering device. In Fig. 1 such barrel is represented as upon an inclined conveyor or elevator B, which may be of any desired character. Where the skid or conveyor is horizontal or at an inclination, the portions of the registering devices will correspond, they being properly shaped and located with reference to the movement of the barrel or other article.

The compound lever is fitted to swing upon a cross-shaft or pivot D, and it is placed so that the barrel or article A can pass freely beneath the pivot and move the compound lever upon its cross-shaft or axis D, and the portion 2, forming a curve or incline in the primary lever C, is in such a position that when the barrel or other article reaches such bend or incline 2 the primary lever C has received all, or nearly all, of the motion that the passing article can give to the same, and upon this primary lever is a secondary lever E, with a projection which is beyond the curve or incline 2, and hence the barrel or other article as it passes along does not give any motion to this secondary lever to change the position of the secondary lever to the primary lever until the primary lever has received the full movement aforesaid, after which the barrel or other article passing along acts upon the projecting end 3 of the secondary lever to change the position of the secondary lever to the primary lever, and in so doing to effect a registration or counting of the article passing along, so that the first movement determines which of the counting or registering devices is to be moved, and the secondary motion effects the movement of that particular counting or registering device.

I have represented at F, G, and H counting or registering devices which may be of any desired character and operated either mechanically or electrically.

In Figs. 1, 2, and 4 the improvement is illustrated in connection with a circuit-breaker for operating the counting devices electrically, and in Fig. 3 the connection is represented as mechanical for moving either one of the counting or registering devices.

It is advantageous to employ a dash-pot K and a connection to the primary lever, which connection is represented in the form of a rod

5, extending from the cylinder of the dash-pot to a hinge connection to such compound lever, and the piston of the dash-pot is sufficiently loose to allow air to pass the same in 5 either direction, but sufficiently tight to prevent a sudden movement of the lever that might allow the lever to drop too rapidly, and I have represented the dash-pot as pivoted at 10, so that the said cylindrical dash-pot can 15 swing upon said pivots as the compound lever rises or falls.

The connection between the secondary lever or projection and the lever C may be of any desired character, having in view the objects to be accomplished, as before expressed. 15 I have, however, represented the secondary lever E as extending to a tube E', that surrounds the cross-shaft D, so that such shaft D becomes the pivot for both levers, and a 20 finger or flange 7 upon the secondary lever E, resting upon the lever C, prevents the lever E from dropping beyond a fixed position and allows such lever E to be raised to give the motion that operates either of the counting 25 devices, and upon the shaft D is an arm C' and upon the tube E' is a second arm E², and these arms C' and E² maintain a definite relative position while the compound lever is being raised or lowered; but when the barrel or 30 other article passes the angle 2 and comes into contact with the projecting end 3 of the lever E the arm E² is moved in its relation to the arm C', and in so doing a movement is obtained that operates the counting or register- 35 ing device. Hence in operating this apparatus the arms C' and E² move together until they come to the proper place for moving the proper register or counting device, and the motion given to the secondary lever E by the 40 barrel or other article acting upon the projection 3 moves the arm E² in its relation to the arm C' and produces the motion that actuates the register allotted to the size of barrel or other article passing beneath or adjacent to 45 the compound lever.

Any suitable device may be employed in giving the movement to the register when the arm E² is moved in its relation to the arm C'. In Fig. 2 I have represented upon the arm C' 50 a ratchet-wheel L and upon the arm E² a spring-pawl N and the insulated circuit-closer upon it, which is near to but not in contact with the separate insulated plates 9 10 11, from which wires pass to the electrically-operated counters or registers F G H, and there 55 is a battery M and return-circuit wire to the spring-pawl N, so that the circuit remains broken, as the pawl may move back or forth adjacent to the contact-plates 9, 10, and 11 by 60 any movement of the compound lever, and when there is a movement given to the arm E² by a passing article moving the secondary lever E in its relation to the primary lever the 65 ratchet-wheel L, and as it is lifted it closes the electric circuit to the proper counter or register and the pawl drops from one tooth to

the other and breaks the circuit before the secondary lever completes its movement, and the compound lever can be moved in either 70 direction until the operations are repeated. The spring-pawl N holds the ratchet-wheel from turning back.

Any suitable character of circuit-closing device can be employed, the same being operated by the movement of the arm E² in its relation to the arm C' after the parts have been brought into position to operate the proper register or counting device.

In Fig. 3 the parts before described are 80 shown without any electrical connections, and the spring-pawl N, as it runs over one of the teeth on the ratchet-wheel, is raised and presses upon one of the segmental ends of one of the levers, Q, R, or S, from which levers 85 wires or other connections lead to the counting or registering devices, and it will be apparent that the compound lever and the arms C' E² can swing in either direction without actuating either of the counting devices until 90 the projection 3 is moved so as to change the relative position of the arm E² to the arm C', and thereby give the motion necessary to actuate the counting or registering devices. The advantage derived from using a ratchet-wheel 95 is that the pawl drops from one tooth to another when the secondary lever is completing its movement. Hence the contact is broken before there can be any other movement given to the levers and a false registration is prevented.

In Figs. 4 and 5 the same devices are represented as in Fig. 1, with the addition of an insulated contact-plate O at the end of the arm C', which rubs upon the plates 9, 10, and 105 11, and the circuit is closed by the pawl with this plate O, instead of directly with either plate 9, 10, or 11.

I claim as my invention—

1. The combination in an automatic indicating and registering device, of separate counting or registering mechanisms, a lever acted upon by the passing barrel or other article, and a secondary lever mechanism carried by the main lever and receiving a movement from the passing article after the main lever has reached its proper position, and a connection actuated by the secondary mechanism for moving the proper counting or registering device, substantially as set forth. 110 115 120

2. In an automatic registering mechanism, the combination with the registers, of a lever moved by the barrel or other passing article into a position corresponding to the register allotted to the given size of barrel or package, 125 and a mechanism carried by such lever and receiving a motion from the passing article to operate the particular register or counting device, substantially as set forth.

3. The combination with the counting or 130 registering devices, of a lever and its shaft, a secondary lever pivoted upon the same shaft, two arms connected to the respective levers there being a projection upon the secondary

lever that is acted upon by the barrel or passing article after the main lever has been moved to the designated position, a spring pawl and a connection to the counting or registering devices brought into action by such spring pawl, substantially as set forth.

4. The combination with the counting registers, of a primary lever receiving its motion from the barrel or other passing article, a secondary mechanism carried by such lever, a circuit closer receiving its motion from the secondary mechanism, a source of electric en-

ergy and a contact plate for each register whereby the circuit closer is first moved to the proper contact plate by the primary lever and then closed by the secondary mechanism, substantially as set forth.

Signed by me this 20th day of February, 1895.

SOLOMON C. WOOD.
